(57) **CLAIM**

The ornamental design for a case for travel items, as shown and described.

DESCRIPTION

FIG. 1 is a perspective view of a case for travel items, showing my new design;

FIG. 2 is a side perspective view;

FIG. 3 is a top perspective view;

FIG. 4 is a bottom perspective view;

FIG. 5 is an end perspective view; and,

FIG. 6 is a perspective view similar to FIG. 1 showing the case for travel items open.

The dashed lines in all figures, as well as the rectangle formed by dotted lines within the rectangle at the center bottom of the case in FIG. 4, indicate stitching and are part of the claimed design.
